US00D954723S

(12) **United States Design Patent** (10) **Patent No.:** **US D954,723 S**
(45) **Date of Patent:** **** Jun. 14, 2022**

(54) **DISPLAY SCREEN OR PORTION THEREOF
WITH GRAPHICAL USER INTERFACE**

(71) Applicant: **SAMSUNG ELECTRONICS CO., LTD.**, Suwon-si (KR)

(72) Inventors: **Kwanghyun Jang**, Suwon-si (KR); **Saebuk Sheen**, Suwon-si (KR); **Jaehan Lee**, Suwon-si (KR)

(73) Assignee: **SAMSUNG ELECTRONICS CO., LTD.**, Gyeonggi-Do (KR)

(**) Term: **15 Years**

(21) Appl. No.: **29/765,838**

(22) Filed: **Jan. 12, 2021**

(30) **Foreign Application Priority Data**

Jul. 24, 2020 (KR) 30-2020-0034430

(57) **CLAIM**

The ornamental design for a display screen or portion thereof with graphical user interface, as shown and described.

DESCRIPTION

FIG. 1 is a front view of a display screen or portion thereof with graphical user interface showing our new design in a first embodiment;

FIG. 2 is a front view of a display screen or portion thereof with graphical user interface showing our new design in a second embodiment;

FIG. 3 is a front view of a display screen or portion thereof with graphical user interface showing our new design in a third embodiment;

FIG. 4 is a front view of a display screen or portion thereof with graphical user interface showing our new design in a fourth embodiment;

FIG. 5 is a front view of a display screen or portion thereof with graphical user interface showing our new design in a fifth embodiment;

FIG. 6 is a front view of a display screen or portion thereof with graphical user interface showing our new design in a sixth embodiment; and,

FIG. 7 is a front view of a display screen or portion thereof with graphical user interface showing our new design in a seventh embodiment.

The outermost broken lines illustrating a display screen or portion thereof form no part of the claimed design. The remainder of the broken lines illustrating portions of the graphical user interface forms no part of the claimed design.

1 Claim, 7 Drawing Sheets
